UNITED STATES PATENT OFFICE.

GEORGE A. LUTZ, OF CRANFORD, NEW JERSEY.

PRIMARY ELECTRIC BATTERY.

1,163,163.

Specification of Letters Patent.

Patented Dec. 7, 1915.

Application filed March 22, 1915. Serial No. 16,232.

To all whom it may concern:

Be it known that I, GEORGE A. LUTZ, a citizen of the United States, and resident of Cranford, in the county of Union and State of New Jersey, have invented certain new and useful Improvements in Primary Electric Batteries, of which the following is a specification.

In primary batteries of the caustic soda or caustic potash type, utilizing a depolarizer in a granular or powdered form, such as cupric oxid, it has been customary, as known to me, to place such depolarizer in a perforated retainer, such as in the well known Gordon battery. The perforations in the retainer, however, have usually been of such area as to permit the finer particles of the depolarizer to sift through, so that losses of depolarizer occur in transporting and handling such retainers, and the depolarizer also is more or less liable to sift through the retainer and lodge in the bottom of the battery jar in use. In Letters Patent Nos. 812,504 and 25 812,505 granted to Charles E. Lockwood and myself February 13, 1906, a binder is disclosed either mixed with the depolarizer or applied upon the perforated container or in the perforations thereof, intended to overcome the disadvantages above mentioned and to permit the charged retainers to be transported and handled without permitting the depolarizer to sift through the perforations of the retainers, which binder becomes dissolved in the battery solution, but the perforations in the retainer were of the character described with respect to the Gordon batteries, and of such area that in the absence of the binder the finer particles of the depolarizer would tend to sift through the perforations in the retainer and be liable to be lodged upon the bottom of the battery jar in use.

The object of my present invention is to provide a container or retainer for such depolarizer for use in primary batteries of the caustic soda or caustic potash type, but made in such form as to enable the binder referred to to be dispensed with when desired, and yet to prevent the finer particles of the depolarizer from sifting through the container, while at the same time permitting access of the caustic solution or electrolyte in the battery to the depolarizer within the container, the container being made of a metal having sufficient strength and rigidity

to support the positive element or zinc without injury to the container. To this end I provide a metallic container for the depolarizer having its walls provided with minute crevices, cracks or slits, longer than wide, and of such narrowness as to practically preclude the particles of the depolarizer within the container from sifting therethrough, yet permitting the entrance therethrough of the battery solution or electrolyte, whereby the container charged with the depolarizer may be shipped and handled without danger of the depolarizer sifting through the same, and may be used in the battery jar without danger of the depolarizer becoming deposited upon the bottom of the jar. The blanks from which the previous metallic container are to be made may be provided with impervious margins around the crevices or minutely slitted portions thereof, to enable adjacent edges of the blank to be rolled or soldered together, as well as to enable similar connection of one or more closures at the end or ends thereof, as in the nature of forming tin cans.

The metal of which my improved container may be made is to be of such a character that the material thereof adjacent to its slitted portions will have sufficient rigidity or resilience as to tend to remain in the normal set position and not be subject to displacement when handled or abused. I prefer a metal which will not disturb the desired working relation of the battery but which will afford the advantages above stated, for which purpose I find sheet iron or copper to be most efficient, since such metal affords the desired electro-chemical reactions and has sufficient strength and resilience and yet can be made sufficiently thin for the purpose of such batteries as to enable the positive element or zinc to be supported thereon, and, by means of suitable insulators, may be secured to the container. The metal to be used in constructing my improved container is such as to have desired conductivity and I find that for the purposes of my invention, including the required strength and rigidity as well as elasticity referred to, my improved pervious containers made of sheet iron or copper as aforesaid afford the desired substantial and efficient construction. If a ductile soft or yielding metal, such as lead, were used for the previous container or wall of my improved battery, the objection would be found that

such container or wall would be subject to distortion or injury in handling, with the objection that the crevices may be either opened too much or closed too tight by displacement of the metal surrounding the slotted portions of the container or wall, or the container might become unduly crushed, and, furthermore, such ductile or similar soft metal would not properly preserve the contour of the container in transportation or handling, since distortion of the container or wall would tend to displace the proper relation of the zinc thereto, with the consequent decrease of efficiency of the battery. 10 Such soft metal container or wall, when made of proper thinness for a caustic battery of the type herein set forth, would not have the desired rigidity and strength to properly support and retain the insulating blocks upon which the zinc element rests or is carried. Such lead container would have too high a resistance and too low conductivity for the purpose of my invention in a caustic battery solution. 20 My invention further comprises novel details of improvement and combinations of parts that will be more fully hereinafter set forth and then pointed out in the claims. 25

Reference is to be had to the accompanying drawings forming part hereof, wherein,

Figure 1 is a vertical section of a primary battery embodying my invention; Fig. 2 is an enlarged detail illustrating a blank for forming my improved container; Fig. 3 is a detail of a portion of Fig. 2 on an exaggerated scale; Fig. 4 is a section on the line 4, 4, in Fig. 3; Fig. 5 is a section on the line 5, 5, in Fig. 3, and Fig. 6 is a section on an exaggerated scale on the line 6, 6, in Fig. 3.

Similar numerals of reference indicate corresponding parts in the several views.

The jar 1, its insulating cover 2, the zinc 3, the insulating support 4 for the zinc, its retaining band 4^a, and the binding post 5 may all be of any usual or suitable construction in this class of battery. The container or wall 6 for the depolarizer 7, such as cupric oxide in granular form, is shown in cylindrical form provided with the closures 8, 8^a at the respective ends of the container, and said container is shown provided with an inner cylinder or wall 9 secured between the closures 8, 8^a. The container is shown supported within the jar by the rod 10 passing through the closures 8, 8^a, and cover 2, and connected with the binding post 5 in a usual manner, and the depolarizer 7 is shown located in the space between such cylinders. The walls of such cylinders are provided with numerous minute crevices, cracks or slits 6^a, which are formed by pressing aside or cracking the metal of the blanks from which the cylinders are made, without dislodging the material of the blanks therefrom, whereby webs 6^b are forced slightly

aside from the plane of the body of the material, producing minute crevices or cracks longer than wide, rendering the completed cylinder or container pervious to the passage of the battery solution or electrolyte, such 70 crevices, however, being so minute as to impede or prevent the sifting therethrough of particles of the depolarizer 7. In the arrangement shown, the crevices or cracks are illustrated in rows, the ends of such crevices 75 or cracks of one row breaking joints with the ends of the crevices or cracks on opposite sides thereof. The connecting pieces 6^c between the corresponding crevices of one row are shown staggered with relation to 80 the pieces 6^c of the rows of crevices on opposite sides thereof, leaving uncut metal between the pieces 6^c and the opposing crevices. As shown in Figs. 2 and 3 an imperforate margin 6^d is provided in the blank outside of the crevices or slits 6^a, whereby two such margins 6^d of the blank may be rolled or soldered together to form the walls of the container or the cylinders 6, 9, thereof, and to enable the edges of the closures 8 to 90 be rolled or soldered in conjunction with an impervious edge 6^d (Fig. 1), as well as providing an impervious edge to receive and be attached to the flange or flanges of closure 8^a, which may be secured to the cylinder or 95 cylinders, after the depolarizer 7 is charged in the container, in a suitable manner.

I have found in practice that the pervious container or wall herein referred to, as formed by slitting the metal to provide 100 minute crevices, should be of such a character as to afford a low internal resistance and at the same time have sufficient strength and rigidity as well as elasticity or resiliency, to properly resist displacement of the 105 metal surrounding the slits or cause the return to normal configuration after temporary distortion so that the crevices will not become unduly opened or closed during handling or transportation, or by strain incident to the support of the positive element or zinc, affording also proper means to secure the insulating blocks 4 to the container or wall for the maintenance of the zinc in proper relation or spacing with respect to 110 the impervious or slotted container or wall. As before stated, a metal, such as sheet iron or copper, may be used for said container or wall to produce the improved results aforesaid. Were a ductile metal, such as lead, 115 used for my improved pervious container or wall, the objections would be found that such metal was of a higher internal resistance than desired, and that such ductile metal would readily permit the displacement of the material surrounding the slits, either tending to open the slits or close them 120 too much, with the consequent undesired increase of flow of electrolyte through the open slits or decrease of flow of electrolyte 125 130

through the closed slits, thereby varying the action of the depolarizer and producing uneven consumption of the active materials. Furthermore, by the use of the slitted sheet 5 iron or copper for the container, I am enabled to pack the cupric oxid depolarizer 7 in the container to a suitable extent, without danger of displacing the material surrounding the slits thereof, whereas if a soft or ductile 10 metal, such as lead, were used for the slitted container, and the depolarizer were packed therein, there would be danger that the metal surrounding such slits would be displaced or pressed away during the packing, 15 with danger of opening or closing the slits too much, producing not only disadvantages in the use of the cell above pointed out, but enabling the more ready sifting out of the depolarizer from the container, either in 20 transportation or in use, with the consequent disadvantages of loss of depolarizer in transportation, depositing of depolarizer in the bottom of the jar or adjacent to the positive element on the insulating blocks, 25 and producing undesired local action. My improvements serve to avoid the objections last named, since the container is constructed of sufficiently rigid material having the electrical properties herein referred to and desired in this form of battery, utilizing a 30 cupric oxid depolarizer and a caustic potash or caustic soda electrolyte. By means of my improvements I obtain full advantage of the use of granular cupric oxid as a depolarizer 35 and am enabled to use such a depolarizer containing very fine particles which may be obtained most readily and at a relatively 40 cheap cost, without the disadvantages which have been incident to re-charging the containers at places where used, or the trouble and expense of applying a binder to the container or wrapping the same in paper or the like to prevent discharge of the depolarizer 45 therefrom during transportation.

45 A further advantage of my improvements is that my improved container or wall may be made cheaper than the wellknown perforated containers heretofore used in caustic batteries, such as in batteries of the Gordon 50 type.

50 A further advantage of my improvements is that all the metal intended for the wall or container is preserved for coaction with the depolarizer, as distinguished from the loss of surface entailed by reason of removing the metal at the perforations.

Having now described my invention what I claim is:—

1. A primary battery element comprising a metal container having a plurality of minute crevices adapted to permit the passage of an electrolyte through the crevices, and to prevent the discharge of a depolarizer through said crevices, said metal having greater conductivity than lead, and having sufficient rigidity to resist displacement of the material surrounding the crevices. 60

2. A primary battery element comprising a container formed of metal having a higher conductivity and being more rigid and resilient than lead, and provided with a plurality of minute crevices adapted to permit the passage of an electrolyte through said crevices and to prevent the discharge of a depolarizer through said crevices. 70

3. A primary battery element comprising a sheet iron container having a plurality of slits forming minute crevices adapted to permit the passage of an electrolyte through said crevices and to prevent the discharge 80 of a depolarizer through said crevices.

4. A primary battery element comprising a plurality of spaced metal walls having closures at their ends, said walls being formed of metal having greater conductivity 85 and greater rigidity and resilience than lead, said walls having slits providing minute crevices adapted to permit the passage of an electrolyte through said crevices and to prevent the discharge of a depolarizer 90 through said crevices.

5. A primary battery comprising a jar, a wall therein formed of metal having greater conductivity than lead, said wall having a plurality of slits providing minute crevices 95 adapted to permit the passage of an electrolyte through said crevices, said wall having sufficient rigidity to resist displacement of the metal surrounding said crevices, a cupric oxid depolarizer in granular form retained by said wall, said crevices being adapted to prevent discharge therethrough of said depolarizer, insulating means to support a positive element adjacent to said wall, and an alkaline solution within the jar. 100

Signed at New York city, in the county of New York, and State of New York, this 19th day of March, A. D. 1915.
